[57] CLAIM

The ornamental design for a soap dish, as shown and described.

DESCRIPTION

FIG. 1 is a perspective view taken from the top, front and right side of a soap dish showing our new design; FIG. 2 is a top plan view thereof; FIG. 3 is a front elevational view thereof; FIG. 4 is a right side elevational view thereof, the left side being the mirror image of the right side shown; FIG. 5 is a bottom plan view thereof; and, FIG. 6 is a rear elevational view thereof.

The fragmentary broken line representation of mounting holes in FIG. 6 is for the purpose of illustration only and forms no part of the claimed design.

FIG. 1

FIG. 2

FIG. 3

FIG. 4

FIG. 5

FIG. 6
